SPIRAL BINDER

Emil N. Farkas, Chicago, Ill., assignor, by direct and mesne assignments, to Emil N. Farkas, Chicago, Ill., as trustee

Application February 29, 1940, Serial No. 321,366

4 Claims. (Cl. 281—25)

This invention relates to new and useful improvements in binders for, and a method of assembling in book form of marginally perforated leaves.

More particularly, the present invention is an improvement on the spiral binder of plastic and highly resilient material disclosed in Patent No. 2,188,680 to Frank F. Farkas, and its object is to preform the binder so that a book bound with it will open with leaves in registry. This I accomplish by forming each loop of the binder so that the helix will have a compound rather than a simple pitch. The spiral is so resilient that it may be readily threaded through the uniformly and equally spaced marginal perforations of a stack of leaves without deformation or tearing of the binder or leaves. The curvatures or slopes of the two halves of each loop are so altered with respect to one another that when the book is opened the two exposed pages engaging opposed points of a loop will be in registry with one another rather than vertically displaced as would be the case if the halves of the loops were uniform.

According to the present invention the binder is formed and set with the loops having the required contours during its manufacture and before it is threaded through the book perforations, thus avoiding the necessity of special operations on the finished book. The invention will now be fully explained with reference to the drawing in which

Fig. 1 is a plan view of one embodiment of my invention at an intermediate stage of its manufacture;

Fig. 2 is a side elevation of a book bound in accordance with the present invention;

Fig. 3 is a side elevation of a spiral binder constructed in accordance with a second embodiment of the invention;

Fig. 4 is a plan view of a third embodiment at an intermediate stage of its manufacture; and

Fig. 5 shows holes suitable for easy insertion of a spiral formed of the strip in Fig. 4.

Referring now to the drawing, 1 is a thin flat strip of plastic material having parallel edges and which is so pliable that it can be readily deformed and yet sufficiently resilient to retain its preformed shape when subjected to normal strains after it is formed into a helical coil.

One edge of strip 1 is mutilated by cutting out unsymmetrical wedges 2 at intervals determined by the diameter required for the loops of the helix. The cut-out occupies about one-half the length required for each loop.

The strip is wound on a mandrel of suitable diameter into a helical coil and subjected to heat and pressure to set it. The strip 1 will thus be formed into a cylinder. When the loops of which the cylinder is made up are pulled out to form open coil, each loop, as far as the edges viewed from the side are concerned, will have two different curvatures: the unmutilated portions, i. e., the left-hand edge and the right-hand edge for about one-half of each loop will form substantially a semicircle, and the mutilated portions will have a different contour, they may be horizontal. In other words the coil will have a compound instead of a uniform or simple pitch. The coil thus formed is sufficiently resilient to permit its threading into the marginal perforations 3 of leaves 4. When a book thus bound is opened the perforations in the right-hand and left-hand leaves will be in alignment since the upper ends of the perforations in the right-hand leaves rest on portions of loops having a curvature different from those portions which bear against the perforations of the left-hand leaves. As indicated in dotted lines in Fig. 2, if the wedges were not cut out of the ribbon and the loops of the helix were of uniform configuration, then the right-hand leaves of the opened book would be vertically displaced out of registry with the left-hand leaves.

Another embodiment of the invention is illustrated in Fig. 3. Instead of mutilating the ribbon, the material has uniform straight sides throughout its length but is formed with a compound pitch, one-half of each loop being formed substantially on a radius and the other half straight or with any other different curvature, as indicated at 5 and 6. When inserted through the perforations of a book, the left-hand leaves of the opened book will engage portions 7 and the right-hand leaves portions 8 of the helix. Since these portions are substantially in alignment, the leaves will be in registry.

This embodiment is particularly recommended for narrow stock, though it is applicable to wide ribbons also.

In the embodiment shown in Fig. 4 a ribbon 10 of plastic material is formed with parallel but undulating edges, the undulations being of two different curvatures 11 and 12, alternating throughout the length of the strip.

When this strip is wound on a cylindrical mandrel and then set, the coil thus formed will have a compound pitch just as in Figs. 2 and 3. The difference is that whereas the helix of Fig. 2 will have a compound pitch along its upper or

supporting edge, the helix formed of strip 10 will have a compound pitch along both edges. With this type of coil the perforations in the book leaves must be large enough to permit threading of the finished coil, and may have other than symmetrical shapes, i. e., different from the usual rectangular or circular holes. Four such holes are shown in Fig. 5.

What is claimed is:

1. A binder for sheets having marginal perforations, consisting of a length of plastic material preformed into a substantially compound pitch helical coil which may be screwed into said perforations, the two halves of each loop forming, at least along one edge of the length of material, a different angle with the longitudinal axis of the coil. 15

2. The binder defined in claim 1 and in which the plastic material is in the form of a ribbon having parallel edges formed into loops with cut-outs along one edge.

3. The binder defined in claim 1 preformed of a plastic ribbon having undulating edges, the undulations being of two different recurring curvatures.

4. The binder defined in claim 1 preformed of plastic material having a substantially uniform surface throughout its length, and in which in one-half of each loop the material forms along both of its edges a different angle with the longitudinal axis of the coil than in the other half.

EMIL N. FARKAS.
